UNITED STATES PATENT OFFICE.

DONALD S. BARROWS, OF ROCHESTER, NEW YORK, ASSIGNOR TO THE T. H. SYMINGTON COMPANY, OF NEW YORK, N. Y., A CORPORATION OF DELAWARE.

DRAFT-RIGGING BACKSTOP.

Application filed October 24, 1921. Serial No. 509,800.

To all whom it may concern:

Be it known that I, DONALD S. BARROWS, a citizen of the United States, residing at Rochester, in the county of Monroe and 5 State of New York, have invented certain new and useful Improvements in Draft-Rigging Backstops; and I do hereby declare the following to be a full, clear, and exact description of the invention, such as will 10 enable others skilled in the art to which it appertains to make and use the same.

My invention relates to draft rigging backstops which are designed to be secured between the center sills or draft sills of 15 a railway car to provide means for transmitting to the car underframing the buffing shocks to which draft rigging mechanism is subjected in service.

The principal object of the invention is 20 to produce a backstop of great strength per unit of weight which may be applied to the car sills with a minimum expenditure of labor and in which shrinkage cracks and similar manufacturing defects are not liable 25 to occur.

The principal feature of the invention, generally stated, consists in constructing a backstop with side walls which are adapted to be secured to spaced car sills and are 30 united at their forward ends by an end wall forming an abutment for a movable part of the draft rigging, a centrally disposed longitudinally extending horizontal web being united to the upper portion of 35 said end wall and extending rearwardly therefrom, and longitudinally extending transversely inclined webs being disposed below said horizontal web and being united at their forward ends to said end wall.

40 A further feature of the invention consists in forming a backstop with side walls which are united by a forward end wall forming an abutment for a movable part of the draft rigging, longitudinally extending downwardly divergent webs being united at their forward ends to said end wall, and a plurality of longitudinally spaced vertical webs being employed for connecting said side walls to the said divergent web.

45 A still further feature of the invention consists in providing a backstop with side walls, a forward end wall uniting said side walls and adapted to form an abutment for a movable part of the draft rigging, a horizontally disposed web connecting the lower

portions of the said side walls, and longitudinally extending downwardly divergent webs uniting said end wall and said horizontally disposed web.

Other features of the invention concerned 60 with special details of construction and their relations will hereinafter appear.

In the drawings illustrating the invention, the scope whereof is pointed out in the claims:—

65 Figure 1 is a plan view of a backstop embodying the invention showing its assembled relation to a portion of the car underframe and to a draft rigging mechanism.

70 Figure 2 is a detail plan view of the backstop.

75 Figure 3 is a rear end elevation of the backstop.

Figure 4 is a vertical sectional view of 75 the backstop, taken to one side of the central web.

Figure 5 is a transverse section on the line 5—5, Fig. 4.

Figure 6 is a section on the line 6—6, 80 Fig. 4.

85 The draft rigging 1 with which the backstop cooperates and the spaced car sills 2 between and to which the backstop is secured may be of any suitable form. In 90 the well known type of draft rigging that is illustrated in the drawings the rear end of the draft yoke 3 is the movable part of the draft rigging which is adapted to communicate buffing shocks to the backstop, 95 but it is to be understood that this special form of draft rigging is merely illustrative and is not disclosed for the purpose of limiting the invention to use in conjunction therewith.

95 The backstop is formed with longitudinally extending side walls 4 which are preferably provided with two vertically spaced parallel rows of openings 5 for receiving rivets 6 whereby the structure may be firmly 100 secured to the sills of the car. At their forward ends the side walls 4 are united by a vertical transversely extending end wall 7 adapted to form an abutment for the movable yoke 3 of the draft rigging.

105 United to the upper part of the forward end wall 7 and extending rearwardly therefrom to the centrally disposed hollow post 8 forming the king bolt opening with which backstops are customarily provided, is a 110

centrally disposed horizontal web 9. Below said horizontal web 9 and preferably integrally united thereto, are longitudinally extending transversely inclined webs 10 which diverge downwardly and are connected to the lower portions of the side walls 4 of the backstop by means of a horizontally disposed web 11. As shown in Figs. 4 and 6, the lower horizontal web 11 10 may be provided with suitable openings 12 for the purpose of coring the space between the downwardly divergent webs 10.

The transversely inclined divergent webs 10 are also united to the side walls 4 by 15 means of a plurality of longitudinally spaced transversely extending vertical webs 13 which preferably are united to the bottom wall or web 11 of the casting and which may conveniently be of less height than the 20 end wall 7. The divergent webs 10 may be advantageously united by a transverse vertical web 14 integrally connected to the lower wall 11 of the backstop. The inclined webs 10 may be integrally connected to the 25 horizontal web 9 through the medium of a centrally disposed vertical web 15.

When the hollow post 8 is employed it is preferred to brace it transversely by vertical webs 16 integrally uniting it to the 30 side walls 4 and to brace it longitudinally by means of a rearwardly extending vertical web 17 connecting it with the lower wall 11 of the backstop.

It will be perceived that by my invention 35 the metal is disposed in a manner to give great strength to the structure while at the same time ample space is afforded for conveniently driving rivets for attaching the backstop to the spaced sills 2 of the car.

40 I claim:—

1. A draft rigging backstop comprising 45 side walls adapted to be secured to spaced car sills, a forward end wall united to said side walls and adapted to form an abutment for a movable part of the draft rigging, a horizontally disposed web connecting the lower portions of said side walls, and downwardly divergent longitudinally extending webs uniting said end wall and 50 said horizontally disposed web.

2. A draft rigging backstop comprising 55 side walls adapted to be secured to spaced car sills, a forward end wall united to said side walls and adapted to form an abutment for a movable part of the draft rigging, transversely inclined webs united to said end wall and extending rearwardly therefrom, and a plurality of longitudinally spaced transversely extending webs united 60 to said inclined webs and to said side walls.

3. A draft rigging backstop comprising 65 side walls adapted to be secured to spaced car sills, a forward end wall united to said side walls and adapted to form an abutment for a movable part of the draft rigging,

longitudinally extending downwardly divergent webs united to said end wall, and a plurality of longitudinally spaced vertical webs connecting said side walls to said divergent webs.

4. A draft rigging backstop comprising 70 side walls adapted to be secured to spaced car sills, a forward end wall united to said side walls and adapted to form an abutment for a movable part of the draft rigging, a centrally disposed longitudinally extending horizontal web united to the upper portion of said end wall and extending rearwardly therefrom, and longitudinally extending transversely inclined webs disposed below 75 said horizontal web and united at their forward ends to said end wall.

5. A draft rigging backstop comprising 80 side walls adapted to be secured to spaced car sills, a forward end wall united to said side walls and adapted to form an abutment for a movable part of the draft rigging, a centrally disposed web united to the upper portion of said end wall and extending rearwardly therefrom between said side walls, and transversely inclined webs connected to 85 and diverging downwardly from said centrally disposed web and united at their forward ends to said end wall.

6. A draft rigging backstop comprising 90 side walls adapted to be secured to spaced car sills, a forward end wall united to said side walls and adapted to form an abutment for a movable part of the draft rigging, downwardly divergent transversely inclined 95 webs united at their forward ends to said end wall, a centrally disposed web united to the upper portion of said end wall and extending rearwardly therefrom between said side walls, and transversely extending webs 100 connecting said centrally disposed web and said divergent webs to said side walls.

7. A draft rigging backstop comprising 105 side walls adapted to be secured to spaced car sills, a forward end wall uniting said side walls and adapted to form an abutment for a movable part of the draft rigging, a plurality of connected centrally disposed downwardly inclined webs, and a transverse web extending between and uniting said inclined webs.

8. A draft rigging backstop comprising 110 side walls adapted to be secured to spaced car sills, a forward end wall uniting said side walls and adapted to form an abutment for a movable part of the draft rigging, inclined webs united to said end wall and extending rearwardly therefrom between said side walls, longitudinally spaced transversely extending webs connecting said inclined webs to said side walls, and a transverse web extending between and connecting 115 said inclined webs.

9. A draft rigging backstop comprising 120 side walls adapted to be secured to spaced car sills, a forward end wall uniting said side walls and adapted to form an abutment for a movable part of the draft rigging, inclined webs united to said end wall and extending rearwardly therefrom between said side walls, longitudinally spaced transversely extending webs connecting said inclined webs to said side walls, and a transverse web extending between and connecting 125 said inclined webs.

10. A draft rigging backstop comprising 130 side walls adapted to be secured to spaced car sills, a forward end wall uniting said side walls and adapted to form an abutment for a movable part of the draft rigging,

car sills, a forward end wall uniting said side walls and adapted to form an abutment for a movable part of the draft rigging, a centrally disposed web united to the upper portion of said end wall and extending rearwardly therefrom between said side walls, inclined webs united at their forward ends to said end wall and extending rearwardly between said side walls, longitudinally spaced transversely extending webs connect-

ing said centrally disposed web and said inclined webs to said side walls, a transversely extending web disposed between and connecting said inclined webs, and a horizontally disposed web connecting said inclined webs to the lower portions of said side walls. 15

In testimony whereof I affix my signature.

DONALD S. BARROWS.
